UNITED STATES PATENT OFFICE

2,408,233

SCREW-THREADED CLOSURE DEVICE

Sydney Hartley Smith, Manchester, England, assignor to Imperial Chemical Industries Limited, a corporation of Great Britain

Application December 21, 1943, Serial No. 515,104
In Great Britain November 13, 1942

4 Claims. (Cl. 220—39)

1

This invention relates to filler caps or closure devices for fuel tanks and other containers and more particularly to means adapted to facilitate rotation of the said devices for attachment to or detachment from a container or the like, said means consisting of two or more pegs or like projections on the outer surface or head of the closure member for engagement with a tommy-bar or other turning lever. The said closure devices may be screw-threaded to engage a corresponding screw thread in the container orifice or may be adapted to be attached to and detached from the container by any other means embodying rotational or semi-rotational movement.

According to the present invention in a closure device of the kind referred to the pegs are adapted to be depressed or lowered and retained within recesses formed in the body of the closure member in such manner that when not in use for rotational movement of the closure, the said pegs are disposed substantially flush with the surface of the closure.

In the best embodiment of the invention, two diametrically opposed spring-loaded pegs are slidably mounted for limited longitudinal movement in bores provided in the head of a closure and are adapted to be depressed into the said bores and retained therein when required by a bayonet type joint.

The aforesaid embodiment of the invention is illustrated in the accompanying drawing in which

Figure 1 is a perspective view of a closure device constructed in accordance with the present invention.

Figure 2 is a perspective view of a portion of the closure illustrated in Figure 1 showing one peg depressed and retained within the closure.

Figure 3 is a sectional view on the line A—A of Figure 1.

Figure 4 is a part-sectional view on the line B—B of Figure 2.

Referring to the drawing a closure member 1, in the form of a plug having an externally screw-threaded portion 1a and a head flange 1b which limits the inward travel of the plug, is provided with two diametrically opposed spring-loaded pegs 2, 2a adapted to be engaged simultaneously by a levering tool such as tommy-bar 3 (shown in chain-dotted lines in Fig. 1) to facilitate rotation of the said closure, said tool having in this instance a flattened or screw-driver end 3a for a purpose hereinafter pointed out. Each of the said pegs is slidably mounted in a cylindrical recess or bore comprising a neck portion 4 leading into an enlarged portion 5 thus forming a shoul-

2

der 6, the said shoulder providing an abutment for an outwardly extending flange 7 on the said peg. The said flange is urged against the said shoulder by means of a spring 8. The neck portion 4 of the said bore is provided with diametrically opposed longitudinal slots 9 which extend the full depth of the said neck portion. Lateral retaining projections 10, such as bayonet pins or arms, protrude outwardly from the peg 2 and engage in the said longitudinal slots, the said pins being adapted to ride clear of the said slots when the peg is fully depressed, thus permitting rotation thereof in the bayonet-joint connection thus constituted and the engagement of the said pins with the shoulder 6 by which means the said peg is retained within the closure, as shown in Figs. 2 and 4. The outer end of the peg is suitably formed, in this instance through provision of kerf 2b, to facilitate its being rotated or turned by a suitable tool when so depressed. The coiled spring 8 is located and compressed between the peg and the disk 11 or the like secured in the base of the closure. To this end, the peg may be shaped like a thimble, as shown, to provide a recess 2c in its base adapted and arranged to cooperate with stud 11a, which projects from disk 11, in suitably confining spring 8.

In order to bring the pegs 2, 2a, into position for levering engagement by a tommy-bar for screwing down or unscrewing the closure device, each peg is rotated or turned, as by suitably engaging the screw-driver end 3a of the tommy-bar of the kerf 2b, until the bayonet pins or arms 10 register with the slots 9, whereupon the spring 8 instantly urges the peg longitudinally through the neck portion 4 of the recess or bore into the position shown in Figs. 1 and 3, this movement being arrested when the peg has attained its proper elevated or protruding position by the engagement of flange 7 with shoulder 6, which elements together constitute stop means.

It will be seen from Fig. 3 of the drawing that the arms 10 of each peg are so spaced from the flange 7, and the shoulder 6 is at such a distance 45 below the outer face of the closure device, that said arms cannot pass upward out of their respective slots but still remain in contact with the walls thereof when the peg projects to its fully elevated or protruding position above said outer face for engagement by a levering bar or tool. It will be further noted that the slots 9, of the pair of spaced recesses housing the cooperating pair of pegs extend in the same direction and are substantially in alignment transversely of the closure. By reason of this construction and ar-

angement, said arms 10 assist in distributing the stresses on the pegs, due to the levering action of the tommy-bar, to the walls of the slots, thereby reducing the danger of bending the protruding portions of the pegs or of unduly compressing the edges of the respective recesses or bores. The most advantageous arrangement is one wherein, as in the specific construction shown, the longitudinal axes of the pegs lie in a diametral plane of the closure device, to which plane all the slot walls are parallel and closely adjacent.

The invention has particular application to filler caps of fuel tanks for aircraft which are required to be flush fitting with the exposed surface of the aircraft wing or fuselage where under flight conditions a smooth flush surface is required and where for filling purposes the filler cap is required to be unscrewed in an easy and rapid manner.

In such circumstances the closure device may conveniently embody a quick-pitch or multi-start screw-thread.

I claim:

1. A closure device which comprises a rotatable closure body provided with a pair of spaced recesses opening outward, each shouldered to provide a neck portion and an enlarged inner portion with a closed base, a peg slidably mounted in each recess for movement between elevated and depressed positions and rotatable in depressed position, said peg being provided with lateral projections working in longitudinal slots in the wall of said neck portion and opening into said enlarged portion, said slots extending in the direction of a straight line passing through both of said recesses, said projections being arranged to ride clear of said slots when the peg is fully depressed and, by then rotating the peg, to be moved under the shoulder of said recess for retaining engagement therewith, a spring compressed between said peg and the base of the recess, and means projecting laterally from said peg adapted and arranged, when said lateral projections are engaged in said slots, to stop outward movement of the peg by engagement with said shoulder, when the peg has been urged outwardly to project a substantial distance beyond said head.

2. A closure device, comprising a closure body having two bores, each closed at its inner end and open at its outer end, each bore comprising a cylindrical portion of enlarged diameter near its inner end and a cylindrical neck portion of smaller diameter at its outer end, to provide an internal shoulder, the neck portion having two slots opening into the enlarged portion of the bore at the shoulder, and all the slots of the two bores extending in the direction of a straight line passing through the diameters of both of said bores, a pair of pegs longitudinally movable in the respective bores between elevated and depressed positions and each adapted to be rotated

about its longitudinal axis in depressed position, each peg being provided with a stop member arranged to engage the shoulder of its bore and thereby limit the outward movement of the peg, and with a pair of diametrically opposite arms which extend laterally from the peg and are adapted and arranged to slide in the slots aforesaid and to pass out of said slots into the enlarged portion of the bore for retaining engagement with the shoulder when the peg, in its depressed position, is rotated about its longitudinal axis; the arms and the stop member being so located and spaced apart in the direction of the longitudinal axis of the peg that, when the stop-device is in contact with the shoulder the upper end of the peg is above the outer face of the closure body sufficiently to be engaged by a tommy-bar and the arms are still within the slots; and resilient means for each peg tending to bring its stop-device in contact with the shoulder of its bore.

3. A closure device, comprising a rotatable body portion having therein two bores, each closed at its inner end and open at its outer end, each bore comprising a cylindrical portion of enlarged diameter near its inner end and a cylindrical neck portion of smaller diameter at its outer end, to provide an internal shoulder, the neck portion having two slots opening into the enlarged portion of the bore and all the slots of the two recesses extending in the direction of a straight line passing through the diameters of both of the bores, a pair of pegs longitudinally movable in the respective bores between elevated and depressed positions, each having provision by which it may be rotated about its longitudinal axis when in depressed position, each peg being thimble-shaped to provide a recess at its lower end, and having a flange arranged to engage the shoulder of its bore to limit the outward movement of the peg, and a pair of diametrically opposite arms which extend laterally from the peg and are adapted and arranged to slide in the respective slots of its bore and to pass out of said slots into the enlarged portion of the bore for retaining engagement with the shoulder when the peg, in its inward position, is rotated on its longitudinal axis; the arms and the flange being so located and spaced apart in the direction of the longitudinal axis of the peg that, when the flange of the peg is in contact with the shoulder, the upper end of the peg is above the outer face of the body portion sufficiently for engagement by a tommy-bar, while the arms are still within the slots; a stud projecting outward from the bottom of each bore, and a coiled compression spring confined by said stud and the wall of the recess in the peg.

4. A closure device as claimed in claim 1 wherein the outer end of each peg is formed to facilitate rotation thereof by an engaging tool when in depressed position.

SYDNEY H. SMITH.
